UNITED STATES PATENT OFFICE.

SAMUEL S. MATTHES, OF MANSFIELD, OHIO, ASSIGNOR TO THE OHIO BRASS COMPANY, OF MANSFIELD, OHIO, A CORPORATION OF NEW JERSEY.

CONDUCTOR SUPPORT.

Application filed February 29, 1924. Serial No. 695,914.

To all whom it may concern:

Be it known that I, SAMUEL S. MATTHES, a citizen of the United States of America, residing at Mansfield, in the county of Rich- 5 land and State of Ohio, have invented cer- tain new and useful Improvements in Con- ductor Supports, of which the following is a specification.

My invention relates to a conductor sup- 10 port and particularly that class of supports for suspending the trolley wire.

The object of my invention is to provide a trolley support of the type known generally as a trolley ear provided with a groove 15 to receive a trolley wire and also provided with lips to be bent or peened around the trolley wire.

Another object of my invention is to so 20 construct the lips that they will give increased wear to the device throughout a large portion of the length thereof and to protect the wire from mechanical injury throughout said length and to provide for the trolley wheel or current collector a 25 smooth and uninterrupted passage from the trolley wire on to the ear and from the ear on to the trolley wire.

In the present type of ears it is the general practice and has been for years, to 30 provide the ear with a groove of uniform length in which the lips are of uniform depth throughout their length and then to taper the lips at the lower edge substantial- 35 ly to a knife edge. This construction I find is not the best as the thinness of the lips at the lower edge where the trolley wheel contacts is the point in the ear where there is the greatest wear on account of the contact with the wheel. Also, extending the 40 lips for full depth to the end of the ear, even though they may be drawn to a knife edge, offers an obstruction to the smooth passage of the wheel from the wire to the ear and from the ear to the wire. This 45 obstruction causes the trolley wheel to jump as it engages the ear and to again contact with the ear at a point somewhere between the ends of the ear and if the ear has been reduced to a substantial knife edge where 50 the re-engagement takes place under con- siderable of a blow the lips of the ear are not only rapidly worn away, but the wire beneath is also injured due to the blow. Likewise, at the leaving end of the ear the

wheel is caused to strike the wire with con- 55 siderable of a blow which multiplied by the number of times a wheel passes over the ear very soon has a detrimental effect upon the trolley wire adjacent the ear.

I have found that by substantially thick- 60 ening the lips of the ear at their lower edge and intermediate the ends of the ear that they will wear many times longer due to normal contact with the trolley wheels, and such trolley blows as they may receive 65 will be absorbed in the lips and not trans- mitted to the wire beneath with ultimate injury to the trolley wire beneath.

Likewise, by properly constructing the 70 end portions of the lips, it is possible to practically reduce the interruption to the 75 smooth passage of the trolley wheel in either direction to a minimum thereby avoiding injury to the trolley wire adjacent to the ear, and also to prevent the trolley wheel jumping as it engages the ear.

In the drawing accompanying this spec- 75 ification:

Fig. 1 is a top plan view of my invention.

Fig. 2 is a side view in elevation.

Fig. 3 is an end view.

Fig. 4 is a sectional view on the line 4—4 of Fig. 2 and substantially to size of a practical working device.

Fig. 5 is a sectional view on the line 55 5—5 of Fig. 2 at a point where I start to change the construction of the lips.

Figs. 6 and 7 are sectional views on the line 6—6 and 7—7, respectively, of Fig. 2.

Fig. 4^A shows the construction in Fig. 4 90 as applied to a trolley wire.

Figs. 5^A, 6^A and 7^A correspond with Figs. 5, 6 and 7, respectively, and show the relation of the lips when applied to the trolley 95 wire.

Fig. 8 shows the under side of a large portion of the ear shown in Fig. 2, but with the lips formed in place about the trolley wire.

In the preferred embodiment of my in- 100 vention I construct a boss 1 which is internally threaded as at 2, in order to attach the ear to an overhead support. The upper end of the boss is provided with a flange 3. The ear is also provided with longitudinal 105 disposed lips 4 forming a groove 5 throughout the length of the ear. The boss is secured to the lip portions as shown and

I also employ diametrically oppositely disposed ribs 6, increasing the attachment of the boss to the lips, also stiffening the lips against being forced upwardly when engaged by the trolley wheel from below. I prefer to make the external width of the lips of uniform width, as indicated by α , through practically the entire length of the ear. This provides a uniform thickness of 10 the lips on the side for wear between any side contact between the lips and the trolley wheel which may take place.

At the point y , which is intermediate the center line of the ear and the end, but not necessarily centrally located therein, I begin to reduce the height of the lips, therefore, reducing the depth of the groove from the point y to the extreme end. This reduction is shown by the space z between the diverging dotted lines in Fig. 2. The lower edge 20 of the lips from the point y to the end of the ear is gradually brought down to a knife edge, as indicated at g and as shown in Figs. 2, 7, 6^A and 7^A, the maximum being 25 reached at the end of the ear and as shown in Figs. 7 and 7^A.

This gradual reduction g , together with the gradual reduction in the depth of the lips provides for a smooth and uninterrupted passage of the trolley wheel on to and off of the ear and it also offers a gradual increase in the exposure of the trolley wire 5 from the point y to the end of the ear as shown in Figs. 7^A and 8.

It might be well to point out here that in the present design of ears of this character it is usual to make the cross section of the ear with tapered or knife edge sections, as indicated in Fig. 7, throughout their length, 40 while it will be noted that in my improved type the full knife edge section is not reached until the end of the ear is approached, as shown in Fig. 7 and no attempt is made to reduce the thickness of the lips until the point y is reached from the center of the ear.

It will be noted that I have provided an ear which has a very substantial thickness of metal throughout the metal in the lips, 50 throughout the length of the ear between the points $y-y$ which increases the life of the ear and eliminates injury to the trolley wire 5 encircled by the lips between the points $y-y$, and that I have also provided a 55 gradual approach for the trolley wheel as it passes from the trolley wire 5 on to the sections $y-y$, and from the sections $y-y$ on to the trolley wire 5, also that the lips throughout the entire length of the ear on 60 the sides thereof are of substantially uniform thickness. The relation of the trolley wheel to the ear is shown in Figs. 4^A to 7^A, inclusive, and it will be recognized by those skilled in the art that the shape of the 65 groove of the trolley wheel, as indicated by

dotted lines in these figures, may vary. I find it practical that a reasonable thickness of the lips at their meeting point, as shown in Figs. 4^A and 5^A is about $\frac{1}{6}$ " to $\frac{3}{2}$ ", although it will be recognized that this may 70 be varied to meet requirements.

Having described my invention, I claim:

1. A conductor support comprising in combination, a support member and a longitudinally disposed member secured to the support member, the longitudinal member comprising oppositely disposed and depending lips forming a groove therebetween to receive the conductor and to be gripped by the lips when bent over, the width of the longitudinal member being substantially uniform throughout its length, the lips substantially meeting for a distance each side of the center line when bent around the conductor and the adjacent edge of the lips for said distance being of substantial thickness, the lips gradually decreasing in height toward each end of the longitudinal member from the point where the lips cease to substantially meet and the outer surface of the lips from said point and along and adjacent the lower edge gradually tapering to a substantial knife edge at the extreme end thereby forming a gradual approach for a current collector from the conductor into the section where the lips substantially meet and vice versa. 85

2. A conductor support comprising in combination, a supporting member and a longitudinally disposed member secured thereto and provided with depending lips forming a groove to receive and hold a conductor when the lips are bent thereabout, the longitudinal member comprising three sections, a central section and two end sections, the lips of the central section adapted to substantially meet when bent about the conductor and having substantial and uniform thickness for the length of said section, the lips of the end sections gradually 100 decreasing in height beginning at the ends of the central section and extending to the ends of the lips and simultaneously decreasing in thickness along their lower edge to a substantial knife edge at their ends for the 105 purpose described.

3. A conductor support comprising in combination, a supporting member and a longitudinally disposed member secured thereto and provided with depending lips forming a groove for the purpose described, the longitudinal member comprising three sections, a central section and two end sections, the lips of the central section adapted to substantially meet when bent about a 120 conductor and having substantial thickness for the length of said section, the lips of the end sections gradually decreasing in thickness from the ends of the central section to the ends of the lips from full thick- 125 130

ness of the central section to a substantial knife edge at the end of the lips, for the purpose described.

4. A conductor support comprising in combination, a supporting member and a longitudinal member secured thereto and provided with depending lips forming a groove for the purpose described, the longitudinal member comprising a central section and an end section extending from the central section to the ends of the longitudinal member, the lips of the central section substantially meeting when bent about the conductor and having a thickness of substantially not less than $\frac{1}{16}$ inch at their adjacent edges, the lips gradually and simultaneously decreasing in height and in thickness along their lower edge from the ends of the central section to the ends of the lips as and for the purpose described.

5. A conductor support comprising in combination, a supporting member and a longitudinal member secured thereto and provided with lips forming a groove for the purpose described, the longitudinal member comprising a central section and end sections extending from the central section to the ends of the longitudinal member, the lips of the central section throughout its length substantially meeting when bent about the conductor and of substantial thickness along their adjacent edges, but gradually diverging from each other and reducing in thickness from the ends of the central section to the ends of the longitudi-

dinal member as and for the purpose described.

6. A conductor support comprising in combination, a supporting member and a longitudinal member secured thereto, the longitudinal member having a uniform portion for a distance in both directions from the center, the uniform portion having bendable lips forming a groove, the longitudinal member also having tapering portions extending beyond the uniform portion in both directions and forming a continuation thereof and having bendable lips forming a groove, the lips of the section gradually tapering along their lower outer edge, both as to height and thickness, as and for the purpose described.

7. A conductor support comprising in combination a supporting member and a longitudinal member, the longitudinal member having a uniform portion for a distance in both directions from the center, and having bendable lips forming a groove, the longitudinal member having tapering portions extending beyond the uniform portion in both directions and forming a continuation thereof and having bendable lips forming a groove, the length of each extension being not less than one half the length of the uniform portion, the lips of the extension gradually tapering along their lower outer edge, both as to height and thickness, as and for the purpose described.

In testimony whereof I affix my signature.
SAMUEL S. MATTHES.
